COMBINATION FACIA AND MOUNTING MEANS

Richard H. Wright, Bratenahl, and Anthony Zay, Cleveland, Ohio, assignors to The Guarantee Specialty Manufacturing Company, Cleveland, Ohio, a corporation

Application April 17, 1950, Serial No. 156,238

3 Claims. (Cl. 248—268)

This invention pertains to the art of window equipment including fixtures designed for supporting Venetian blinds, shades or the like, with which decorative or finishing facias are used.

A common type of facia now employed for combining with blinds or shades is made of metal which may be pressed to afford decorative characteristics, and largely comprising a channel of suitable length having entwined flanges for adding strength or rigidity. This type of facia is bent or curved laterally at its ends to form entwined closing end extensions to house the head bar or rail of a Venetian blind and be disposed at their extremities proximate to the window frame, while the facia body is spaced from such frame in front of said head rail as usual.

The present invention comprises a facia, such as above referred to, combined with bracket supporting means attachable to a window frame and of novel form adapted to engage the end extensions of the facia to firmly hold the latter in place on the window by a quickly performed frictional engaging action, which, however, permits of ready separation of the parts whenever desirable, as for demounting the parts. Said bracket means has provisions to support the head rail.

In carrying out the invention, advantage is taken of the curved end sections of the facia by which the top and bottom edge flanges are caused to be positioned close to the body portion of the facia at the end corners, the special bracket means employed in the combination structure being capable of being readily forced into wedging engagement with the said flanges for supporting the facia without resorting to use of special separate fastening means heretofore necessary for the purpose.

Another object of this invention has been to combine curtain rod mounting means with the bracket unit of the invention so that a rod may be supported on a pair of such units behind the facia also carried thereby.

A full understanding of the invention and the merits thereof will be had on reference to the following specification, and to the accompanying drawings, in which latter:

Figure 1 is a top plan view showing equipment contemplated by the invention, including a pair of head rail supporting brackets, a head rail mounted thereon, suitable mounting means for a curtain rod located outwardly of the head rail, combined with a facia of the metal construction hereinbefore referred to, with all of said parts in operative relation as when in use.

Figure 2 is a rear elevation of the invention as seen with the associated parts as mentioned in conjunction with the description of Figure 1, the view being taken on the line 2—2 of Figure 1, looking in the direction of the arrows.

Figure 3 is a vertical sectional view taken on about line 3—3 of Figure 2.

Figure 4 is a detailed perspective view of one of the bracket units forming a part of the invention.

Figure 5 is a fragmentary view showing a modified form of bracket unit in which the curtain rod supporting extension is integral with the body of the bracket as distinguished from the attachment type of construction illustrated in the other figures of the drawings.

Figure 6 is a fragmentary sectional view taken about on the line 6—6 of Figure 2 and bringing out more clearly the manner in which each of the brackets for supporting the facia is adapted to be wedgingly engaged with one of the extensions of the facia by frictional wedging action.

2

Figure 7 is a detail perspective view showing an attachable shade roller supporting bracket member capable of being interlocked with the shelf on the bracket which supports the Venetian blind head rail so that if a roller shade is to be mounted in rear of the facia, in lieu of the head rail, the bracket unit is convertible for use with either such shade or head rail.

Similar reference characters refer to like parts throughout the drawings and in the following description of the construction of the invention.

The construction of the facia in conjunction with which the present invention is used in peculiar combinative relation will first be described.

The said facia is generally designated at A and is comprised, as best seen in Figure 3, of a metal plate which may be formed with pressed out ribs 1 longitudinally thereof for reinforcement or decorative purposes. At its upper and lower edges, the facia is provided with an inwardly flange 2 which is bent in a direction laterally from the body of the facia, and then bent in a direction parallel with said body to provide a secondary flange 3. The flange parts 2 and 3 are provided primarily to stiffen the facia structure at its upper and lower edges. As customary, the facia must be made of a width which corresponds with the width of the space between the sides of a window frame and when this width is determined, the end portions of the ordinarily straight facia plate bodies, are bent laterally or substantially to positions in which are provided end extensions A' at right angles to the plane of the front body portion of the facia. In order to facilitate the proper bending of the extension A' from the front portion of the facia A, sections of the flanges 3 are bent or pressed to positions in which they extend at an acute angle to the plane of the flanges 2, as seen in dotted lines at 3a, primarily upon reference to Figure 2 and also Figure 3. This bending action brings the free edges of the flanges 2 at the portions 3a, very close to the body portions of the extension A' projecting rearwardly from the front body of the facia, and this construction is taken advantage of in establishing cooperation between the supporting brackets for the facia in a manner which will shortly be described.

The construction of the brackets or bracket units of the invention will next be set forth upon reference particularly to Figures 3 and 4 of the drawings.

Each bracket is designated 4 and comprises a body plate or section formed at its rear edge with a right-angled extending mounting flange 5 provided with screw apertures 6 for the passing therethrough of screws for attaching the brackets 4 to a side of a window frame. The body structure of the bracket may be formed with corrugation sections 6 to reinforce and strengthen the same for purposes of rigidity.

At its upper portion a section of the metal of the bracket 4 is struck laterally therefrom to provide the head rail supporting shelf 7 which also may have apertures 8 for screws to pass through to facilitate attachment of the head rail thereto.

A typical form of head rail is designated at 9 and shown in Figures 1, 2 and 3 of the drawings.

At the front or outer edge of the bracket 4, or the edge opposite that having the mounting flange 5 thereon, there is located the curtain rod supporting bracket member 10 which may be mounted on the body of the bracket by means of a rivet 11 and by means of a lug 12 struck out from the bracket body and interlocked in a notch portion 13 on the inner end of the bracket member 10, or on an inwardly extending extension 10a of said member 10. The outer end of the bracket member 10 is provided with a notch 14 in its upper edge to provide a seat for one end of a curtain rod 15 that may be mounted upon a pair of bracket members 10 carried by a pair of brackets 4 secured to opposite sides of the frame of a window, as obvious from Figures 1 and 2.

It is essential to the inventions that the upper and lower horizontal edge portions of the brackets 4 shall be free in order that they may be forced into the space between the flanges 3 and the outer body portions of the facia, as the facia is pushed rearwardly onto the said brackets when disposed upon the window frame in attached positions. Thus, a movement rearwardly of the

facia with its extension A' by which the said extensions are engaged with and over the upper and lower edges of the brackets 4 will cause the sliding of the said extensions A' onto the brackets, and effect a wedging interengagement of the upper and lower outer corner portions of the bracket in the wedging spaces B between the bent flange portions 3a and the body portions of the facia. In other words, the portions of the brackets 4 just mentioned are adapted to impinge in these wedging spaces with the parts of the flanges 3a that converge outwardly towards the body of the facia extensions A and by frictional engagement in the manner stated, the facia will be firmly maintained in interlocked engagement with the brackets without the necessity of having recourse to any additional fastening means whatsoever. In other words, the upper and lower edges of the brackets 4 at the portions opposite the mounting flange 5, or adjacent the edge opposite the mounting flange 5 will effect a locking engagement of the facia extensions A' on the bracket in the manner above stated.

If it is desirable at any time to detach the facia A, a sufficient outward pull thereof from the central portion will disengage the end extensions A' from the brackets 4 and at the same time enable the bodily removal of the Venetian blind head rail curtain rod 15 supported on the bracket members 10.

Figure 5 shows a modified form of bracket member 10, designated 10a, in which said member is stamped out of the material from which the body plate of the bracket 4a, in integral formation with the latter.

It may be desirable at times to avail of the bracket and facia combination means of the invention for supporting a shade or curtain roller. Under such conditions it is desirable that the roller be mounted at a height on the bracket 4 about where the interchangeable Venetian blind head rail is ordinarily located. With this in view, there may be provided an attachable shade roller pintle supporting bracket member 16, such as shown in Figure 7 of the drawing. The member 16 is provided with the bracket arm 17 extending vertically therefrom and formed with the slotted portions to receive the flat pintle member located at one end of a shade roller, as commonly used. Two projections, stamped downwardly from the base plate of the member 16 and of hook-like formation, may be caused to enter the openings 8 in the head rail shelf 7 of the bracket 4 and thus interlock the member 16 to the latter, when the head rail is removed, and a curtain or shade roller is to be mounted in place on the brackets 4 instead of said head rail. The bracket member 16 constructed to receive the round pintle at one end of a shade roller may be provided at its vertical arm 17 with an aperture instead of the slot which is shown in Figure 7, such construction being mechanically obvious.

Of course, it will be understood that the combination of parts including the facia A and brackets 4 may be availed of without the use of the curtain rod supporting means shown or with it, as found desirable.

Having thus described my invention, what I claim as new and desire to secure by Letters Patent of the United States is:

- 5 1. A mounting bracket of the class described, comprising in combination, a body having a mounting member formed therewith, said body being engageable with a facia at opposite edges thereof, a shelf formed integrally with the body and pressed therefrom so as to extend at substantially right angles thereto, said shelf being provided with spaced openings and being adapted to support a head rail thereon, and a removable shade supporting bracket member seated on said shelf, said member having a base plate engaging said shelf and a bracket arm formed therewith extending vertically therefrom, said base plate being formed with hook-like members engaged in the spaced openings in the shelf aforesaid.
- 10 2. The combination as claimed in claim 1, wherein the base plate of the removable bracket member is substantially co-extensive with the shelf, and the hook-like members are formed at one edge of the base plate, and extended downwardly therefrom into the spaced openings in the shelf which are located near the free edge of the latter.
- 15 3. In facia and bracket equipment, the combination of a facia for window mounting, said facia being provided with ends, each of said ends formed with a bracket receiving portion, and a pair of brackets each having a body, each of said bodies having a mounting member attachable to a window frame, the body portion of each 20 of the brackets being substantially completely received in one of the bracket receiving portions of the facia ends, to hold the facia detachably in position on the brackets, each of said brackets being formed with a shelf extending toward the other bracket, and a shade supporting 25 bracket carried by each of said shelves, each shelf having a vertical opening near its free edge, and each shade bracket having a base portion having at least one downwardly and laterally extending hook-like projection to interlock in said opening, and a shade supporting member 30 extending up from the bracket.
- 35 40
